UNITED STATES PATENT OFFICE

165,281

WIRE PULLING AND TWISTING TOOL

Carl H. Goodson, Jacksonville, Tex.

Application March 26, 1951, Serial No. 14,628

Term of patent 14 years

(Cl. D54—13)

To all whom it may concern:

Be it known that I, Carl H. Goodson, a citizen of the United States of America, residing at Jacksonville, Cherokee County, State of Texas, have invented a new, original, and ornamental Design for a Wire Pulling and Twisting Tool, of which the following is a specification, reference being made to the accompanying drawing, forming a part thereof.

Fig. 1 is a perspective view of the top and one side of a wire pulling and twisting tool, showing my new design; and Fig. 2 is a perspective view of the top and other side thereof.

I claim:

The ornamental design for a wire pulling and twisting tool, as shown.

CARL H. GOODSON.
